UNITED STATES PATENT OFFICE.

BERNARD H. SPECKBAUCH, OF NEWPORT, KENTUCKY.

PRINTING-PRESS.

SPECIFICATION forming part of Letters Patent No. 643,692, dated February 20, 1900.

Application filed September 27, 1899. Serial No. 731,799. (No model.)

To all whom it may concern:

Be it known that I, BERNARD H. SPECKBAUCH, a citizen of the United States, residing at Newport, Campbell county, Kentucky, (post-office address, 332 West Ninth street, Newport, Kentucky,) have invented certain new and useful Improvements in Printing-Presses, of which the following is a specification.

10 This invention pertains to improvements in perfecting printing-presses adapted for single-color or multicolor printing; and the improvements will be readily understood from the following description, taken in connection 15 with the accompanying drawings, in which—

Figure 1 is a side elevation of a printing-press exemplifying my improvements; Fig. 2, a view from a similar direction, one of the housings being removed and the printing, impression, and inking rolls appearing in vertical section in the plane of line *a* of Figs. 4, 5, and 9; Fig. 3, a side elevation of one of the printing-cylinders, illustrating a construction peculiarly adapted for use in the printing of 25 the longitudinally-striped portion of flags—as, for instance, the American flag; Fig. 4, a view of the face of the web as produced by the printing-cylinder illustrated in Fig. 3; Fig. 5, a longitudinal section of the printing-cylinder shown in Fig. 3, the section appearing in the plane of line *e* of Figs. 2, 6, 7, and 8; Fig. 6, a vertical transverse section of the same printing-cylinder in the plane of line *d* of Figs. 3 and 5; Fig. 7, a similar section in 30 the plane of line *c* of Figs. 3 and 5; Fig. 8, a similar section in the plane of line *d* of Figs. 3 and 5; Fig. 9, a side elevation of the impression-cylinder, and Fig. 10 an end elevation of a portion of the impression-cylinder.

40 In the drawings, referring for the present exclusively to Fig. 2, 1 indicates the side housings of the press; 2, the impression-cylinder; 3, its elastic jacket, as of sheet-rubber; 4, the upper printing-cylinder, carrying a printing-form for the upper side of the web or sheet to be printed, this printing-cylinder coöperating with the impression-cylinder and moving at the same peripheral rate of speed; 5, the lower printing-cylinder, carrying a form 45 corresponding with the lower face of the web or sheet to be printed, this printing-cylinder coöperating with the impression-cylinder and

moving at the same peripheral rate of speed; 6, inking-roll for the upper printing-cylinder; 7, inking-roll for the lower printing-cylinder; 55 8, supply-roll of the fabric to be printed; 9, a pair of draw-rolls, the fabric from the supply-roll 8 passing between impression-cylinder 2 and upper printing-cylinder 4 and thence between the draw-rolls, the draw-rolls 60 and the three cylinders having, preferably, the same diameter and all moving at the same peripheral rate of speed.

Let it be assumed that the opposite surfaces of the web are to be printed alike in exact register with each other—as, for instance, in the American flag—showing alike on both sides, the two sides being in exact register, but one side being the reverse of the other, or, so to speak, one side “right-handed” and one side 70 “left-handed.” Assume the press as being employed for the production of the red or striped work of such flags. In such case both ink-rolls 6 and 7 are to supply red ink to their respective printing-cylinders. 75

As the web passes between the impression-cylinder 2 and the upper printing-cylinder 4 the upper surface of the web will obviously become impressed by the form carried by the upper printing-cylinder, such impression, 80 however, being, as usual, the reverse of the form which produced it. At the same time the lower printing-cylinder 5 prints upon the jacket 3 of the impression-cylinder 2 an impression the reverse of the form carried by 85 the lower printing-cylinder, and at each turn of the cylinders this impression, carried by the jacket of the impression-cylinder, comes against the lower surface of the web opposite the form upon the upper printing-cylinder 90 and becomes transferred to the lower surface of the web in reverse of the impression thus brought around by the impression-cylinder, thus printing both sides of the web. As the jacket of the impression-cylinder received an 95 impression in reverse of the form on the lower printing-cylinder and as that impression reversed itself in becoming transferred to the under surface of the fabric, it is obvious that the under surface of the fabric receives an impression corresponding precisely with the form on the lower printing-cylinder—that is to say, unreversed. As the two sides of the fabric are to be printed in reverse of each 100

other, it is obvious that the two forms, the one on the upper printing-cylinder and the one on the lower printing-cylinder, must be exactly alike, the upper form imprinting itself in reverse upon one side of the fabric, while the lower form sends its impression to the lower surface of the fabric through the medium of two reversals. In case the lower surface of the fabric was printed direct from a printing-cylinder, as is the case with the uppersurface, it is obvious that the two forms would require to be the reverse of each other, thus involving great skill in the production of the forms; but in the present case the two forms are identical with each other, and no skill is required in securing proper correspondence between them. The two forms, identical with each other, being secured to their respective printing-cylinders, it is only requisite that the two forms be so angularly adjusted upon their cylinders as to secure proper register. This may be done by angularly adjusting one cylinder with reference to the other or by angularly adjusting the form upon one of the cylinders. The draw-rolls 9 having the same diameters as the printing-cylinders, it is obvious that if the fresh printing upon the web causes a set-off on the draw-rolls such set-off will impress itself in proper place upon the web in correspondence with the printing thereon, and thus do no harm. In the example given—that of the stripe part of the American flag—both the printing-forms would be supplied with red ink; but it is obvious that the system lends itself to printing with varying colors upon the opposite sides of the fabric. Thus, for instance, the upper printing-roll may be inked red and the lower printing-roll be inked blue, thus printing the upper side of the fabric in red and printing upon the lower side of the fabric an accurately-registering reverse impression in blue. In the American flag, as an example, there are two colors upon each side, being thus an example of multicolor printing. If the cylinders of my improved press, as represented in Fig. 2, are to be employed for producing one of the colors—as, for instance, the red portion of the American flag—then the blue portion will be produced by subsequent subjection of the running fabric to a second similar series of three cylinders, the two printing-cylinders carrying the forms precisely alike and suited for the blue work, and similarly the web may be subjected to the action of as many such separate series of three cylinders each as there are colors to be produced upon each side of the fabric, this method of multicolor printing by running the fabric through various sets of printing-rolls in succession not being new.

I will now describe an improved construction for the printing-cylinders adapted for the printing of longitudinal stripes—as, for instance, in the American flag.

Referring further to the drawings, 10 in Fig. 4 indicates a strip of fabric printed with

the red stripes of numerous American flags of various sizes adapted to fill up the fabric; 11, the largest flag of the series upon the strip, 70 the length of this flag being less than the circumference of the printing-cylinders and its width being less than that of the strip of fabric, three repetitions of this flag appearing in so much of the strip as is shown; 12, a transverse series of three small flags, their combined widths equaling the width of large flag 11, and the length of the small flags 12, plus the length of large flag 11, plus the space between their ends, corresponding with the 80 circumference of the printing-cylinders, there thus being a group of the small flags 12 interposed between each of the large flags 11; 13, a longitudinal series of three medium-sized flags disposed alongside the previously-85 mentioned flags, the length of this series of medium-sized flags, plus the spaces between them, corresponding with the circumference of the printing-cylinder and coming even endwise with the group represented by the large 90 flag 11 and small flags 12; 14, a space transversely across the strip of fabric between each complete group of flags, by "complete group" being meant a large flag 11, three small flags 12 at its end, and three medium-sized flags 95 13 alongside the large and small flags, each of these groups of large, small, and medium-sized flags, together with the space 14 between them, representing the circumference of the printing-cylinders and being repeated on the 100 web at each turn of the printing-cylinders, and 15 the fields or unstriped portions of the flags, being the portions which are to receive the blue printing.

Referring to Fig. 4, assume, first, that only 105 the large flags 11 be desired. The length of such flag is less than the circumference of the printing-cylinder. Hence a space corresponding with the length of flags 12 would be wasted in the operation of printing. Side 110 wastage may of course be avoided by using a strip of only needed width; but to avoid wastage between the ends of the large flags the small flags 12 or any other matter of suitable size are printed, and for economy in time and 115 labor a wide strip is preferably used and flags printed alongside the large flags. With a printing-cylinder having a circumference and length suited to a given very large market size of printed flag it will be found that this 120 dimension of printing-cylinder well lends itself to division after the general manner indicated in Fig. 4 to the printing of smaller market sizes without waste of printing-space upon the strip, and the same principle of division 125 may be followed in connection with articles other than American flags.

Proceeding with the drawings, 16 indicates the shaft of the printing-cylinder, which will now be spoken of in the singular, as the two 130 printing-cylinders become duplicates of each other; 17, the bearers of the printing-cylinders, having the form of disks fast on the shaft; 18, three disks secured upon the shaft

of the printing-cylinder and having a diameter equal to that of the bearers 17, the peripheries of these disks forming printing-surfaces and their widths, spacing, and disposition on the shaft being in correspondence with the three long stripes of flag 11, (seen in Fig. 4;) 19, four similar disks upon the shaft corresponding in width, spacing, and position with the four shorter stripes of flag 11, 5 these disks being preferably separately strung upon the shaft of the printing-cylinder and properly spaced apart by collars or hubs; 20, cut-away portions in the peripheries of disks 18 and 19 at points where no stripes are to be 10 printed by those disks, the bottom of these cut-away portions being concentric with the axis of the disks and their lengths varying according to circumstances, the length in disk 18 being represented by the length of flags 12 15 plus space 14, as seen in Fig. 4, while in disks 19 it is represented by the length of flags 12 plus space 14 plus the length of the field in flag 11; 20 21, printing-plates secured to the bottoms of cut-away portions 20 of disks 18 and 19, the 25 outer-surfaces of these plates being circumferentially even with bearers 17 and the printing-surfaces of the disks, these printing-plates corresponding with flags 12 of Fig. 4, there being a separate plate for each of the three 30 flags 12 or one plate for the three, as desired; 22, three printing-disks strung upon the shaft and corresponding in width and spacing with the three long stripes of flags 13, (seen in Fig. 4,) these disks forming the long stripes for the 35 three flags of the group 13; 23, a bolt extending through the bearers and disks of the printing-cylinders and serving to dowel the parts in proper angular position; 24, four printing-disks upon the shaft in correspondence with the short stripes of flags 13; 25, cut-away portions or notches in disks 22, corresponding with the spaces between the ends of the flags of group 13 and representing the usual blank stick-spaces on printed flags, 40 disks 24 having similar cut-away spaces extended in length to allow for the unstriped fields of the flags; 26, the bearers of impression-cylinder 2; 27, a longitudinal slot in the shell of the impression-cylinder; 28, a reel- 45 shaft longitudinally disposed within the impression-cylinder just within slot 27; 29, spurs oppositely projecting from the reel-shaft and engaged by the jacket 3 of the impression-cylinder; 30, a ratchet-wheel on an end of the 50 reel-shaft projecting from the end of the impression-cylinder, which projecting end is secured for convenience in turning the reel-shaft; 31, a bolt engaging the ratchet-wheel, and 32 the exemplifying transmitting-gear- 55 60 ing of the system, consisting of a receiving-pulley communicating motion by spur-gearing to the cylinders and draw-rolls.

Referring to Fig. 2, in applying the jacket 3 to the impression-cylinder 2 one end of the 65 jacket is hooked to one series of spurs on the reel-shaft 28 and the reel-shaft partially turned, after which the jacket is brought

around the impression-cylinder and hooked to the other series of spurs, whereupon the turning of the reel-shaft reels up both ends 70 of the jacket and strains it nicely upon the impression-cylinder. This construction permits of a very narrow slot 27 in the impression-cylinder. The slot in the impression-cylinder represents a waste space in the printing system, a space on which there must be a blank or non-printing space on the printing-cylinders. Referring to Fig. 4, this space is utilized at space 14, disposed endwise between flags. Whatever may be the relationship of 75 the various flags of the groups, otherwise none of them are to cross the space 14. The blank space 14 may thus serve as the stick-space for all the flags contiguous to it.

Comparing Figs. 3, 4, and 5, it will be observed that all the stripes of the large flags 11 and of the medium flags 13 are printed by means of the disks and that the small flags 12 are printed by means of printing-plates secured in the cut away portions of disks employed in printing large flags. The space represented by flags 12 and the printing-plates which produce them may of course be filled up with printing-plates suited for articles other than flags or, if waste be ignored, may be left blank. The disks 22 and 24 for flags 13 may be removed or may be replaced by others suited for other dimensions of flags, and printing-plates may be used in conjunction with them or not, as desired. Printing-plates 21 may be removed and changed without disturbing any disks.

I claim as my invention—

1. In a printing-press, the combination, substantially as set forth, of a printing-cylinder having a printing-surface in relief, an inking-roll therefor, an impression-cylinder running in direct contact with said printing-cylinder and having a yielding surface, and an additional cylinder coöperating with said impression-cylinder and having a printing-surface in relief in duplicate of said printing-cylinder, said impression-cylinder and additional cylinder being arranged to have a fabric passed between them, and an inking-roll coöperating with said additional cylinder.

2. In a printing-press, the combination, substantially as set forth, of an impression-cylinder having a yielding surface, a printing-cylinder disposed over said impression-cylinder and having a printing-surface in relief, an inking-roll for said printing-cylinder, an additional cylinder disposed below said impression-cylinder and running in direct contact therewith and having a printing-surface in relief in duplicate of said printing-cylinder, and an inking-roll coöperating with said additional cylinder, and means for drawing a fabric between said printing-cylinder and impression-cylinder.

3. In a printing-press, the combination, substantially as set forth, of a pair of printing-cylinders with printing-surfaces in relief in duplicate of each other, an inking-roll for

each of said printing-cylinders, an impression-cylinder coöperating with both of said printing-cylinders and having a yielding surface, and a pair of draw-rolls having diameters 5 and surface speeds the same as said printing-cylinders.

4. In a printing-press, the combination, substantially as set forth, of an impression-cylinder provided with a yielding peripheral surface having a slot extending lengthwise of the cylinder, a pair of printing-cylinders coöperating with said impression-cylinder and provided with printing-surfaces in relief and having spaces of interruption extending 10 lengthwise of the cylinders, said printing-cylinders and impression-cylinder being so related that as they turn together said interruptions in the printing-cylinders will register with the slot in the impression-cylinder, 15 20 an inking-roll for each of said printing-cylinders, and means for drawing a fabric between said impression-cylinder and one of said printing-cylinders.

5. In a printing-press, the combination, 25 substantially as set forth, of a shaft, a series of separated disks secured thereon and having their peripheral surfaces gapped or interrupted, an impression-cylinder running in contact with the peripheries of said disks and 30 having a yielding surface, an inking-roll coöperating with the surfaces of said disks, a cylinder running in direct contact with said impression-cylinder and having a printing-surface in relief, an inking-roll for said printing-cylinder, and means for drawing a fabric 35 between said impression-cylinder and said disks.

6. In a printing-press, the combination, substantially as set forth, of a shaft, a series 40 of separated disks secured thereon and hav-

ing portions of their peripheral surfaces radially and concentrically reduced, curved relief-printing plates secured to the reduced peripheral surfaces of said disks and bridging between them and having their outer surfaces 45 disposed in the arc of the outer peripheries of said disks, an inking-roll coöperating with the surfaces of said disks and printing-plates, an impression-cylinder coöperating with said disks and printing-plates and having a yielding surface, a cylinder running in direct contact with said impression-cylinder and having printing-surfaces in relief, an inking-roll for said printing-cylinder, and means for drawing 50 a fabric between said disks and printing-plates and said impression-cylinder.

7. In a printing-press, the combination, substantially as set forth, of a shaft, a series of separated disks thereon, each of said disks having a gapped or interrupted periphery, an additional series of separated disks upon said shaft, each of said last-mentioned disks having a plurality of gaps or interruptions in its periphery, one of the gaps in each of said last-mentioned disks being in line with the gaps 65 in the first-mentioned disks, an inking-roll coöperating with said disks, an impression-cylinder coöperating with the peripheries of said disks and having a yielding surface, a printing-cylinder running in direct contact 70 with said impression-cylinder and having printing-surfaces in relief, an inking-roll for said printing-cylinder, and means for drawing a fabric between said impression-cylinder and the peripheries of said disks.
